UNITED STATES PATENT OFFICE.

EDWARD THOMAS PERRY, OF DETROIT, MICHIGAN, ASSIGNOR OF ONE-HALF TO
HENRY M. WIEGAND, OF DETROIT, MICHIGAN.

BAFFLE-PLATE.

1,343,376.

Specification of Letters Patent. Patented June 15, 1920.

Application filed January 7, 1920. Serial No. 349,995.

To all whom it may concern:

Be it known that I, EDWARD T. PERRY, a citizen of the United States, residing at Detroit, in the county of Wayne and State 5 of Michigan, have invented a new and useful Baffle-Plate, of which the following is a specification.

This invention relates to new and useful improvements in baffle plates to be employed 10 in connection with engine cylinders for restricting the quantity of lubricating oil entering the cylinders, thus preventing the flooding of the cylinders to the end that any possibility of the engine smoking as a 15 result of burning excess oil, is absolutely eliminated.

An object of this invention is to provide a baffle plate having means to permit oil to pass from the cylinders into the crank 20 case of the engine, in the event that too great a quantity of oil enters the cylinders.

A further object of the invention is to provide a device of this character which may be readily and easily attached to engine cylinders now in use, and one which 25 will prevent oil from finding its way between the baffle plate and the cylinder to which the same is applied.

With the foregoing and other objects in 30 view which will appear as the description proceeds, the invention resides in the combination and arrangement of parts and in the details of construction hereinafter described and claimed, it being understood 35 that changes in the precise embodiment of the invention herein disclosed, may be made within the scope of what is claimed, without departing from the spirit of the invention.

40 Referring to the drawing:—

Figure 1 illustrates a fragmental sectional view through a cylinder having the device applied thereto,

45 Fig. 2 illustrates a sectional view taken on line 2—2 of Fig. 3, and

Fig. 3 illustrates a plan view of the same.

Referring to the drawing in detail, the reference character 5 designates the body of the plate which is formed of any suitable 50 metal, the same being preferably circular in formation, and of a diameter to properly fit adjacent the open end of an engine cylinder.

As shown, the plate includes a concaved body portion indicated at 6, providing an oil 55 receiving pan which is provided with a cen-

tral slotted portion 7, the slot being of a width to accommodate the usual piston rod, to permit the same to operate in the cylinder to which the device forming the subject matter of the invention is applied.

Relatively long inwardly extending flanges 8, form the walls of the slotted portion 7, the flanges 8 lying in spaced relation with each other, and in positions to permit the operation of the piston rod therebetween.

An outer ring 9 is secured to the side walls of the baffle plate, the same being of a width equal to the side walls of the baffle plate, and are provided with an annular shoulder 70 10, formed by the offset portion 11 of the ring 9, which shoulder is constructed to support the packing ring 12 which packing ring is provided for closely engaging the outer edge of the block in which the cylinder supplied with the baffle plate, is formed, thereby preventing the passage of oil between the baffle plate and the engine cylinder.

Laterally extending ears 13 are formed on the ring 9, and disposed in spaced relation with each other, these ears being apertured as at 14 to receive securing bolts by means of which the baffle plate may be secured to the engine cylinder to prevent displacement of the baffle plate.

Openings 15 are provided adjacent the side walls of the baffle plate, which openings permit excess oil, which might find its way to the interior of the cylinder, to pass from 90 the cylinder, and into the crank case of the engine.

Disposed in the side walls of the body 5, are oblong openings 16, which openings permit oil to enter the body, from the sides 95 thereof, the size of these openings 16 being governed by the amount of oil consumed by various makes of engines.

From the foregoing it is obvious that a baffle plate constructed in accordance with the present invention is particularly adapted for use in connection with engines wherein the splash system is employed for lubricating the engine cylinders, thus it will be seen that due to the concaved body portion the 105 crank shaft, which operates in close proximity to the lower ends of the cylinders will have ample room to permit the same to throw lubricating oil to the interior of the cylinder, but at the same time, the flanges 110

8 prevent excess quantities of oil entering the cylinders.

Having thus described the invention, what I claim as new is:—

- 5 In combination with the open end of an engine cylinder, a baffle plate for substantially closing the open end of the cylinder, the baffle plate having a sectional bottom, each section being concaved, a relatively
- 10 long inwardly extending flange having connection with each section, the flanges being disposed in spaced relation with each other,

and the walls of said baffle plate being provided with openings adjacent the lower edges thereof for permitting oil to pass 15 from within the baffle plate.

In testimony that I claim the foregoing as my own, I have hereto affixed my signature in the presence of two witnesses.

EDWARD THOMAS PERRY.
